Actg.

United States Patent Office.

CHARLES H. LANDENBERGER, OF PHILADELPHIA, PENNSYLVANIA.

Design No. 4,555, dated January 3, 1871.

DESIGN FOR A SHAWL.

The Schedule referred to in these Letters Patent and making part of the same.

To all whom it may concern:

Be it known that I, CHARLES H. LANDENBERGER, of Philadelphia, in the county of Philadelphia and in the State of Pennsylvania, have invented certain new and useful Improvements in Design for Woven Shawls; and do hereby declare that the following is a full, clear, and exact description thereof, reference being had to the accompanying drawing and to the letters of reference marked thereon making a part of this specification.

My design consists of a shawl, having a stripe, series of stripes, or other border, on or near two of its edges at opposite ends, and facing on opposite sides.

Figure 1 in the accompanying drawing shows one pattern of my shawl spread or unfolded.

Figure 2 shows a shawl folded over in the form in which it is worn.

In the drawing I have represented a shawl with a plain ground or center, having a series of stripes, A, at one edge or side and a like series of stripes, B, at the opposite side or edge, the two facing on reverse sides.

The border may be a stripe or series of stripes, A and B, or it may be varied to include other ornamental figures, flowers, squares, or other shaped figure, either with or without stripes, which may vary in dimensions and color.

The center or ground portion of the shawl may be plain, as shown, or of any other design or pattern common to the article.

What I claim as new, and desire to secure by Letters Patent, is—

The design for a shawl, substantially as described and illustrated.

In testimony that I claim the foregoing I have hereunto set my hand and seal this 29th day of November, 1870.

CHARLES H. LANDENBERGER.
